UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,288,662.

Specification of Letters Patent. Patented Dec. 24, 1918.

Application filed May 21, 1917. Serial No. 170,022.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a simple and efficient draft rigging.

In the drawings forming a part of this specification, Figure 1 is a horizontal section of a draft rigging embodying my invention; Fig. 2 is a cross section taken on line 2—2 of Fig. 1. Fig. 3 is a partial longitudinal vertical section taken on lines 3—3 of Fig. 1. Fig. 4 is a perspective view of one of the movable plates. Fig. 5 is a perspective view of one of the stationary plates.

Referring to the drawings, the numerals 10—10 indicate center sills for a draft member, being parts of the car underframe to which the draft rigging is applied. Front stop members are shown at 11—11; rear stop members at 12—12. The draft gear is indicated at 13, the same being supported by the tie-plate 14, which is removably secured to the draft member as, for instance, by the bolts 15—15. A yoke 16 connects the draft gear to the draw-bar 17. The front follower 18 is of a usual type and performs the usual function. The draft gear 13 comprises a shell 19. The shell is open at its front end and closed at its rear end by the preferably integral plate 20 which performs the function of a rear follower. At its front end the shell is provided with a series of spaced-apart stationary plates 21 arranged in sets 22 and 23 on either side of the open forward end of the shell. Movable plates 24 are alternately arranged between the stationary plates 21. An internal follower 25 is mounted between the shell. Interposed between it and the closed rear end of the shell are the springs 26—26. Along its forward face the internal follower 25 is provided with the mortises 27—27 to receive the double tenons 28—28 with which the rear edges of the movable

plate 24 are provided. In this manner the movable plates are secured to the internal follower 25. The stationary plates 21 are provided with upper and lower notches or grooves 29—29 to receive within them the transverse ribs or keys 30—30 with which the shell is provided. By means of this arrangement, the stationary plates 21 are held against longitudinal movement, but are permitted a slight lateral movement as required. Spreading members 31—32 are mounted between the two sets of plates 22 and 23, and include the rear wedge 31 which engages the internal follower 25, the front wedges 32—32 which engage the front follower 18, which members are adapted to spread to force the movable and immovable or stationary friction plates into frictional engagement with each other.

On rearward movement of the draw-bar, the front follower forces the spreading members into wedging engagement against the set of friction plates on either side thereof, the internal follower is forced rearwardly, thus drawing rearwardly the movable plates which are meanwhile engaged frictionally by the stationary plate, the rearward movement of the internal follower 25 being also resisted by the springs 26—26.

In the form of my invention shown in the drawings, the friction plates are arranged at an angle to the axis of the shell, to thus cause a flexing of the plates and give a higher frictional resistance.

On forward movement of the draw-bar, the shell is drawn forwardly by means of the yoke, the wedges 32—32 are stopped by the front follower 18, and the action of the parts within the shell is similar to that upon buffing movement.

I claim:

1. In a draft rigging for railway cars, a shell, springs within the shell, an internal follower associated with said springs, movable friction plates connected to the internal follower, stationary friction plates associated with the movable plates, and spreading means to force the movable and stationary friction plates into frictional engagement with each other.
2. In a draft rigging for railway cars, in combination: a shell; alternately arranged movable and stationary friction plates in said shell; means to force said plates into frictional engagement with each other;

spring means to resist the movement of the movable friction plates; means associated with the movable plates to impart motion thereto; the friction plates being angularly arranged to the axis of the shell, whereby the movable plates will be flexed on movement.

3. In a draft rigging for railway cars, in combination: a shell; stationary friction plates associated therewith; movable friction plates alternately arranged between the stationary plates; means to force said plates into frictional engagement with each other; a follower connected to the movable plates; spring means to resist the movement of said plates; the said plates being obliquely arranged in reference to the axis of the shell.

4. In a draft rigging, in combination; a shell; stationary friction plates and movable friction plates associated therewith within said shell; wedging means forcing said plates into engagement with each other; a follower and springs; the follower and the movable plates being provided with inter-engaging securing means; said friction

plates being obliquely arranged in reference to the axis of the shell.

5. In a draft rigging for railway cars, the combination with a shell, of stationary friction plates and movable friction plates associated with said shell, wedging means for forcing said plates into frictional engagement with each other upon actuation of the draft rigging, a follower within the shell and having the adjacent ends of the movable friction plates attached thereto, spring means between said follower and the shell, an outside follower spaced from the adjacent ends of the movable friction plates, said wedging means being interposed between said inner and outer followers and adapted to transmit pressure longitudinally from the outer follower to the inner follower whereby the latter pulls the movable friction plates relatively to the shell.

In witness that I claim the foregoing I have hereunto subscribed my name this 30th day of April, 1917.

JOHN F. O'CONNOR.
